UNITED STATES PATENT OFFICE

2,094,166

FENCE WIRE STRETCHER

Edward Bockenhauer, Waterman, Ill.

Application November 3, 1936, Serial No. 109,013

1 Claim. (Cl. 24—133)

This invention relates to implements and tools now frequently referred to in the trade as fence wire pullers, stretchers, and the like, and it obviously has reference to a device which is attachable to a fence wire so that it may be drawn taut and satisfactorily nailed or otherwise anchored to the post.

Needless to say, I am aware that the art to which the invention relates is characterized by numerous forms and types of tools. It follows, therefore, that the present invention relates to a tool possessed of distinctively new mechanical characteristics and expressly designed so that the harder the clamp is pulled, the tighter it grips the wire.

Briefly, the preferred embodiment of the invention comprises a clamp unit composed of a pair of companion grips pivotally attached together at one end and having their intermediate portions fashioned to securely maintain the wire therebetween, the free ends of said members having associated therewith chain accommodation means providing the desired progressive take-up and clamping action.

Although novelty is predicated upon the central formation of the co-acting clamping surfaces between the companion or complementary gripping units, the chief novelty resides in the free end construction of said units, wherein one unit is provided with a self-adapting roller and attaching links which, when associated with the pull chain provides the desired friction grip tightening action.

Other features and advantages will become more readily apparent from the following description and drawings.

In the drawings, wherein like numerals are employed to designate like parts throughout the views:

40 Figure 1 is a side elevational view of a tool or implement constructed in accordance with the present invention, showing the manner in which it is connected with the wire and block and tackle power appliance.

45 Figure 2 is a view on an enlarged scale which may be designated as a top plan view, that is, a view looking down on top of the structure seen in Figure 1.

Figure 3 is a proportionately enlarged side elevational view disclosing the jaw formation and illustrating the inserted position of the free end of the fencewire.

50 Figures 4 and 5 are enlarged cross sectional views taken on the planes of the lines 4—4 and 55 5—5 respectively of Figure 1.

Figure 6 is a detail sectional view which may be said to be taken approximately on the plane of the line 6—6 of Figure 3.

Figure 7 is a fragmentary bottom plan view of the left hand end portion of the tool.

Reference is had as a matter of convenience, to the enlarged showing of the tool illustrated in Figure 3. Here, and as before indicated, the major part of the structure is made up of a pair of complementary lever-type frictional gripping jaws 8 and 9 to accommodate and receive the strand or length of fence wire 10. In side elevational view these parts 8 and 9 represent compound curves. Moreover, each lever is of one-piece formation and includes a plate portion and a reinforcing rib 11. The left hand end portions of the levers are pivotally joined together as indicated at 12 and one lever is offset as denoted at 13 in Figure 7 to permit this connection to be satisfactorily made. The jaw unit 9 includes longitudinally spaced wire gripping surfaces 14 and 15, and an intervening downwardly bowed central portion 16 which functions as an adapter for the convexed correspondingly curved portion 17 constituting the central portion or part of the jaw unit 8. The latter unit 8 also includes the surfaces 14a and 15a which match with the gripping surfaces 14 and 15 to securely maintain the wire therebetween. The wire is held against sidewise displacement through the instrumentality of a pair of spaced parallel upstanding flanges 18 formed on the unit 9 and bridging the clearance pocket 16.

It will be observed that the free swingable end portions of the jaw units 8 and 9 are directed laterally in diverging relationship. The ends 19 of the unit 9 terminate in an offset terminal 20 suitably positioned to accommodate a pair of links 21. The links are disposed in spaced parallel order and pivotally attached to said terminal 20 as indicated at the point 22. Between the free swingable ends of the links is an idling roller 23 for cooperation with the pull chain 24. One link of the chain 24 is releasably engageable with the eye 25 formed on the free end of the laterally directed end portion 26 of the lever 8. The numeral 27 designates a slot in the eye which allows the chain links to be releasably connected therewith. The hook 28 on the free end of the chain is engageable with the conventional block and tackle assembly 29 which is in turn connected with a suitable cable leading to a winding and reeling device or suitable windlass (not shown). By inserting the fence wire between the jaw units 8 and 9, it is firmly held between the cooperating

surfaces 14, 14a, 15 and 15a. The wire bridges the gap formed by the receding central curved portion 16 and is forced down into this by the convexed clamping member 17. The result is that these co-acting features unquestionably grip the wire with requisite certainty to guard against accidental slippage.

5 The flanges 18 serve to not only accommodate and hold in place swingable lever unit or jaw 8, but they also facilitate threading and placing the fence wire in place. The laterally directed 10 free ends 19 and 26 disposed in diverging relationship, allow the links and roller means to cooperate with the chain 24 and the eye 25 in producing the desired progressive take-up action. Consequently, the tighter the chain is pulled, the 15 tighter the jaws 8 and 9 are clamped against the wire. It follows therefore, that the wire can be safely and tautly stretched to permit it to be 20 nailed or otherwise anchored on the fence post.

Novelty apparently resides in the serpentine curvature of the jaw members 8 and 9. That is to say, by using a compound curve in the longitudinal formation of these parts, the desired co-acting 25 clamping surfaces are provided therebetween to insure effective binding of the wire. The stabilizing flanges 18 also contribute their proportionate share to the feature of strength and durability and safe maintenance of the wire. The 30 cardinal feature of the invention however resides in the free end formation of the lever-like jaw and the chain and pulley arrangement co-operable therewith. The so-called pulley, made up

of the parts 21 and 23 forms a sort of a floating abutment which exerts the desired cam action to effectively bind the jaws together.

It is thought that the description taken in connection with the drawings will enable a clear 5 understanding of the invention to be had. Therefore, a more lengthy description is thought unnecessary.

While the preferred embodiment of the invention has been shown and described, it is to be 10 understood that minor changes coming within the field of invention claimed will be resorted to if desired.

I claim:

A clamp for stretching fence wire comprising 15 a pair of complementary clamping jaws, respectively, pivotally connected together at corresponding ends and provided intermediate their ends with concave and convex mating portions, respectively, for gripping the wire therebetween, 20 a pair of side flanges, respectively, on the jaw having the concave portion, for guiding the wire into position over the latter and the other jaw into closing position, said jaws having divergent free ends, a pair of opposed links pivotally connected at one end to the free ends of one jaw, a pulley mounted between the other ends of said links, and a pull chain secured to the free end of the other jaw and extended between said links for engagement with said pulley, said links being 25 shorter than the distance between the free ends of the jaws in the closed position of the latter.

EDWARD BOCKENHAUER.
